UNITED STATES PATENT OFFICE.

JEREMIAH SWEITZER, OF MISHAWAKA, INDIANA.

IMPROVEMENT IN PLOWS.

Specification forming part of Letters Patent No. 31,194, dated January 22, 1861.

To all whom it may concern:

Be it known that I, JEREMIAH SWEITZER, of Mishawaka, county of St. Joseph, and State of Indiana, have invented a new and valuable Improvement in Plows; and I do hereby declare that the following is a full and complete description thereof, reference being had to the accompanying drawings, and to the letters of reference marked thereon.

The nature of my invention consists in the arrangement of the several parts of the plow, as hereinafter set forth.

Figure 1 is a side view of the plow.

Fig. 2 is a plan showing the position of the beam B and the landside b, by which it will be seen that the beam is straight with the landside, and consequently makes a straight draft. In the same figure o is the bent standard, and c the brace upon which the land-side handle rests.

Fig. 3 represents the position of the handle a and brace c c, the brace c c having a flange,

s s, (more plainly shown in Fig. 1,) extending a short distance up the handle a and strengthening the handle and brace. b is the landside. The handle a, from the beam B to the brace c c, is in the same plane with the beam. Above the beam it is bent away from the handle a' sufficient to give the proper spread to the upper end of the handles. The lower end of the handle a is secured to the brace c c, by which the standard o is strengthened, and the rubbish allowed to escape without clogging.

What I claim as my invention, and desire to secure by Letters Patent, is—

The arrangement of the beam B, handles a a', landside b, standard o, and brace c c with flange s, the whole constructed as and for the purposes set forth.

JEREMIAH SWEITZER.
